FERDINAND W. MOSTERTZ, OF PHILADELPHIA, PENNSYLVANIA

MATCH STRIKER FOR MATCH FOLDERS

Application filed April 3, 1928. Serial No. 267,067.

This invention relates to folding holders for matches, which are carried by a card, and more especially to a striker, which heretofore has been attached to the turned over end of the folding holder. The majority of persons using this kind of a holder usually opens the folding holder, detach a match, and before closing the holder strike the match on a striker, and quite often, especially where the person is inattentive, possibly attention being attracted in other directions, the supply of matches catch on fire from the flame of the match being lighted, therefore it is the purpose of the present invention to avoid this difficulty.

The above difficulty is overcome by attaching or making the striker an attached or permanent part of the flap of the holder on the exterior thereof, necessitating the user closing the flap of the holder, so as to cover the other matches and avoid setting them on fire, and yet enabling the user to have a comparatively rigid support when the holder is held in the hand for striking the match.

Another purpose is to mount or attach the striker on the flap in such a manner that when the flap is inserted under the folded end of the holder, the edge of the striker or striker strip will abut against the underturned end of the back of the holder, and thus provide for a comparatively rigid support when the holder is held in the hand for striking the match.

It is to be understood that the particulars herein given are in no way limitive, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1 is a view in perspective of a folding paper or cardboard holder having a plurality of matches connected in the customary manner to the card board or paper holder, showing the striker as applied.

Figure 2 is a longitudinal sectional view

through the folding holder, with the folding flap overlying the matches, with the end of the folded part engaging under the folded end of the back of the holder, showing the abutting engagement of the striker with the turned over end of the back.

Referring to the drawings: 1 identifies the folding holder, which may be constructed of any suitable material preferably relatively thin card board, though not extremely pliable but substantially so as to permit the proper holding of the matches 2. The matches 2 are in series and are made of paper pulp card board, approximately three sheets of such paper pulp card board, one above the other and fastened by a wire 3 within the folding holder. These sheets of paper pulp card board are slotted at 4 to make the proper size of matches, having the usual igniting material on their ends.

The back of the folding holder at one end is extended, and this extended part 5 overlies the matches, where they are secured in the holder. The extreme edge of this turned over part 5 may be sprung from the surface of the matches to permit the extreme edge of the folding flap 6 to engage under the extreme edge of the back.

Secured by any suitable means preferably a piece of wire 7, to the outer face of the folding flap is a striker 8, and this striker is so disposed that one of its edges may abut at 9, the edge of the turned over extremity of the back of the holder thereby providing a comparatively rigid support of the folding flap, when the holder is held in the hand for striking a match.

The invention having been set forth, what is claimed is:—

As an article of manufacture, a match box comprising a match card and a cover flap for said card to encompass the same, said card having an extension at its base edge bent over engaged with and secured to the base ends of the matches, a match striker strip fastened on the outer face of the cover a short distance from the free end edge of the cover, whereby the free end portion may engage under and between the extension and

the base portions of the matches, so that one edge of said match striker strip may engage with the free edge of the extension and limit the under insertion of the free edge of the cover.

5 In testimony whereof he affixes his signature.

FERDINAND W. MOSTERTZ.
